Primary Examiner—Philip S Hyder*Assistant Examiner*—Cynthia Underwood(74) *Attorney, Agent, or Firm*—Mark Douma**CLAIM**

I claim the ornamental design for a drinking vessel, as shown and described.

DESCRIPTION

FIG. 1 is a top and side perspective view of a drinking vessel showing my new design;

FIG. 2 is a side elevation view thereof, wherein all the claimed elements appear the same from all sides;

FIG. 3 is a top plan view thereof;

FIG. 4 is a bottom plan view thereof;

FIG. 5 is a vertical longitudinal sectional view along line 5—5 of FIG. 3;

FIG. 6 is a top and side perspective view of a second embodiment showing my new design;

FIG. 7 is a side elevation view thereof, wherein all the claimed elements appear the same from all sides;

FIG. 8 is a top plan view thereof;

FIG. 9 is a bottom plan view thereof; and,

FIG. 10 is a vertical longitudinal sectional view along line 10—10 of FIG. 8.
